UNITED STATES PATENT OFFICE.

CARLOS HOLLY, OF LOCKPORT, NEW YORK, ASSIGNOR TO THE F. N. BURT COMPANY, LIMITED, OF BUFFALO, NEW YORK, A CORPORATION OF ONTARIO, CANADA.

BINDER-GLUING DEVICE.

1,034,710.

Specification of Letters Patent.

Patented Aug. 6, 1912.

Original application filed April 24, 1909, Serial No. 492,029. Divided and this application filed February 25, 1911. Serial No. 610,765.

To all whom it may concern:

Be it known that I, CARLOS HOLLY, a citizen of the United States, residing at Lockport, in the county of Niagara and State of New York, have invented certain new and useful Improvements in Binder-Gluing Devices, of which the following is a full, clear, and exact description, such as will enable others skilled in the art to which it appertains to make and use the same.

This invention relates to gluing devices, and more particularly to devices for applying an adhesive, such as glue, paste, etc., to a continuous web as it is fed past the adhesive supply.

One of the objects of the invention is the provision of efficient means for feeding the adhesive and applying the same uniformly over a surface of the web.

Another object is the production of a simple device to control the thickness of the adhesive on the web.

Still another object is the provision of a practical apparatus for applying adhesive to a continuous web of comparatively thin material, and for tensioning said web so that it will be held in efficient contact with the adhesive or glue supplying devices.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein similar reference characters refer to similar parts throughout the several views, Figure 1 is a sectional elevation of the gluing and tension device showing the preferred feeding mechanism for the web; Fig. 2 is a plan view of the device; Fig. 3 is a vertical transverse section of the device; and Fig. 4 is a side elevation thereof.

This application is a division of applicant's prior application No. 492,029, filed April 24, 1909, in which is disclosed a ma-

chine for making paper boxes from continuous webs of paper.

The present application relates particularly to the gluing devices for the binder web as disclosed in the application above identified, but it will be understood that the invention herein disclosed is not restricted to such application, but is intended to be employed wherever useful.

webs which are employed as covers or binders for boxes are often thin so as to be very pliable, having little stiffness, and it is one of the objects of my invention to efficiently apply a uniform surface of glue to a web of this character. Being thin and pliable, it is preferred to feed the web past the gluing devices by the mechanism described in my aforesaid application, in which the web is drawn past and in contact with the glue feeding roller. It is deemed unnecessary to illustrate the web feeding means in entire detail as said feeding means alone is not claimed in this application.

In Fig. 1 of the drawings the gluing and tension device is illustrated in its preferred association with the web feeding mechanism of the application above identified. The numeral 1 indicates the frame of the box making machine, in which is supported a roll of web 2 of paper or similar material suitable to cover and form a binder for a paper box. Preferably this web is of thin paper, glazed on one surface, the glue to be applied to the unglazed surface. The roll of web 2 is supported on a mandrel or drum 3 the web being led from the rear side of the roll downwardly in a loop, thence passing over the front of the roll of web through the tension device and into contact with the gluing device, being then led to a point where its end portion is seized by oscillating grippers 4 which feed or draw the web intermittently past the tension devices and the gluing apparatus. The means for feeding the web is similar to that disclosed in the prior application, and generally described, comprises two gripper fingers 5 and 6 adapted to approach and recede from each other, and to be oscillated

by the shaft 7 by means of the arm 9 connected to said shaft and a connecting rod 10 operated by an elbow lever 11, which is actuated by a cam 12 on a shaft 13. Rotation of the shaft 13 causes the cam 12 to move the lever 11 to intermittently oscillate the grippers to feed the web forwardly, the return movement of the grippers being accomplished by the spring 14 secured to the elbow lever and the frame of the machine. In order to relieve the gripper feeding mechanism from the resistance of the entire roll of web as the web is fed, a pull bar 15 extends through the loop and is connected to a rock shaft 16 having an arm 17, a cam 18 on the shaft 13 serving to vibrate the pull bar to unwind the roll 2 sufficiently to provide a slack portion of web, and this slack portion comprises the weight of web which is fed by the grippers.

It will be understood that the means for driving the shaft 13 to oscillate the grippers and vibrate the pull bar are similar to the means disclosed in the prior application, and it will also be understood that the mechanism to open and close the grippers at the proper times is similar to that in said prior application.

The numeral 19 indicates the web, and from the rear side of the supply roll 2 the web passes downwardly and then upwardly along the front side of the same, forming a depending loop below the roll, thence rearwardly, in zigzag fashion alternately with its opposite sides in engagement with a front horizontal tension roller 20 and a plurality of rear tension or retarding rods or bars 21, 22, 23 arranged horizontally one behind the other in a longitudinal row, thence over the top of the periphery of a glue feeding or delivery roller 24, thence over a scraper 25, thence upwardly around an adjusting roller 26 and through a throat or guide-way formed between the front end of the flange web feed table, as disclosed in my prior application, and a guide bar 27 arranged transversely in front of this table, and thence horizontally forward over the upper edge of this guide bar. In passing successively over and underneath the tension roller and bars or rods, a frictional resistance or tension is produced on the web which operates to retard the forward movement of the web, and causes the same to always remain comparatively taut in passing over the glue applying roller, scraper, adjusting roller and the guide bar 27, and thereby enables these parts to operate properly upon this web. For the purpose of applying a further tensioning and braking effect on the web, a removable presser block 28 is provided which has a felt facing 29 on its under side whereby the same engages with the top of the web as the same passes

between the bars 21, 23 and which has a weight 30 on its upper side for producing the desired pressure. As the web passes around the tension roller 20 and the several tension rods, the same is also guided so as to be held in the proper position laterally for subsequent operation. For this purpose two side guides 31, 32 are provided which are capable of lateral adjustment, the left guide 31 being adjustably connected with the adjacent stationary part of the machine, in the present instance the glue pot which is bolted to the frame, by a transverse adjusting screw 33 and slideable on the roller 20 and rods 21, 23, which are held relatively stationary by a bracket 34 connected with one, 80 end thereof, and the right hand guide 32 being shifted transversely by connecting the same with the right end of the rod 22 which is slideable in the left guide 31 and adjustably connected therewith by a set screw 35. The lower part of the glue supply roller is immersed in a bath of liquid glue contained in a supply tank or pot 36 below the delivery roller, the glue being retained in a liquid condition of the proper consistency by a heating or warming device of any suitable construction, but preferably by means of a jacket 37 which is arranged adjacent to the lower front side of the glue tank or pot and through which hot water, steam or other heating medium is circulated by any suitable means. As the web is drawn rearwardly over the top of the periphery of the glue delivery roller, the latter deposits a coat of glue on the respective side of the web and the delivery roller is turned by frictional contact with this web, thereby causing the same to constantly pick up new glue and delivering the same to the following parts of the web.

For the purpose of causing a greater or less portion of the web to engage with the glue delivery roller and thus vary the amount of glue which is picked up by the web from this roller, the web adjusting roller is provided with means whereby the same may be raised or lowered relatively to the scraper, which means are also so constructed that the adjusting roller may be lifted clear of the glue pot and delivery roller when access is required to these parts for cleaning, inspection or repairs. The means for this purpose which are preferred comprise a pair of rock arms 38 which are pivoted at their front ends for vertical rotation on opposite sides of the front part of the glue pot and pivotally support the adjusting roller at its opposite ends, a spring 39 being connected with one of the rock arms 38 and the frame and tending normally to raise the adjusting roller, a hook or catch 40 adapted to engage with a pin or shoulder 41 on one of the adjusting roller

arms and hold the latter in its lowered operative position, an elbow lever 42 pivoted on the side of the glue pot and having the hook or catch 40 pivoted on one of its arms, 5 an adjusting rod 43 passing through a lug 44 on the side of the glue pot and pivotally connected at its front end with the other arm of the elbow lever, a spring 45 surrounding the adjusting rod between the lug 10 44 on the glue pot and a collar 46 on the rod and operating to push the rod forwardly, and a screw nut 47 applied to the threaded rear end of the adjusting rod and engaging with the rear side of the lug 44. 15 Upon turning the screw nut 47 in one direction or the other, the same in coöperation with the spring 45 causes the adjusting rod 43 to be moved either forwardly or backwardly and thus turn the elbow lever 42 so 20 that the adjusting roller 26 is either raised or lowered, thereby enabling the web to be deflected more or less by the scraper and thereby vary the scarfing effect of the latter and leaving a film or coating of glue on the 25 web of the desired thickness. When the adjusting roller 26 is to be temporarily raised clear of the glue pot and delivery roller, this may be done quickly and conveniently by disengaging the catch 40 of the elbow lever from the respective arm of the adjusting roller and when the latter is again returned to its operative position the same may be as quickly held in place by reengaging the catch of the elbow lever with the 30 shoulder or pin on the respective adjusting roller supporting arm. It will be observed that this construction provides for the adjustment of the web guide 26 relative to the web delivery roller 24 and thus the extent 35 of surface contact of the web and the roller 24 may be varied, resulting in the application of more or less glue to the surface of the web. And it will be further noted that by disengaging the catch 40 from the arm 40 carrying the adjusting roller, said roller may be raised into such a position either by hand or by its spring 39 to permit the ready unthreading or re-threading of the web and that when the adjusting roller is returned 45 to its operative position and reengaged by the catch 40, it will assume its original position, the catch 40 and its operating devices thus operating as a setting mechanism for the adjusting roller; this setting mechanism 50 being adjustable as before explained, so as to determine different operative positions of the adjusting roller 26 when desired. The surplus glue which is removed by the 55 scraper from the web is returned to the pot. 60 In order to permit the scraper to be adjusted so that it is parallel with the web and leaves a film of glue thereon which is of uniform thickness all the way across the web, means are provided for adjusting this

scraper relatively to the coated surface of 65 the web, consisting of a bracket 48 rising from one side of the glue pot and supporting the fixed end of the scraper, a rock lever 49 pivoted on the opposite side of the glue pot and having one of its arms connected 70 with the other movable end of the scraper, a vertical adjusting screw 50 connected at its lower end with the glue pot and passing upwardly through the other arm of the scraper adjusting lever, a spring 51 surrounding 75 the adjusting screw between the top of the glue pot and the underside of the scraper lever and operating to turn the lever, when free, in the direction for lowering the movable end of the scraper, and a screw nut 52 which is applied to the upper threaded end of the adjusting screw and bears against the rear arm of the scraper lever which when tightened causes the 80 scraper lever to be turned in the direction 85 for elevating the movable end of the scraper and move the same toward the coated surface of the web, thereby enabling the scraper to be placed in parallelism with the 90 web for obtaining a film of glue of uniform thickness throughout its width.

The tension devices hereinbefore described may be supported and secured in position by any suitable means, but it is preferred to provide the pot at its upper portion with 95 forwardly projecting perforated lugs 53 and to support the guide rods 31 and 32 on a rod 54 passing through the openings in said lugs, said rod also supporting at its end the bracket 34. To securely brace the tension 100 devices, the guide rods are provided with depending arms 55 which rest against the front wall of the pot.

In the present embodiment the rock arm 38 on the left side of the pot is provided 105 with an arm 56, substantially parallel with the arm 38, the pin 41 extending through the arm 56. By this construction the pin 41 is securely braced and the arm 56 serves as a handle for manipulating the roller 26. 110

As the web 19 is drawn forward by the oscillating gripping devices, the tension devices cause the web to taunt and to contact with the glue applying roller in its forward movement, the amount of longitudinal surface contact being regulated by the position of the adjusting roller 26. By said roller 26 a partial governing of the amount of glue supplied to the web is effected. The scraper bar may be set to determine the ultimate 115 thickness or depth of the glue allowed to remain on the web, being a very accurate means of regulation, especially for thin films of glue. By varying the weight 30, more or less tension may be applied to the 120 web, varying also the gluing effect of the roller 24 and the scarfing effect of the 125 scraper.

Thus it will be perceived that by the above described apparatus is provided a device which accomplishes, among others, the objects hereinbefore stated.

- 5 As many changes could be made in the above construction and many apparently widely different embodiments of this invention could be made without departing from the scope thereof, it is intended that all 10 matter contained in the above description or shown in the accompanying drawings shall be interpreted as illustrative and not in a limiting sense. It is also to be understood that the language used in the following 15 claims is intended to cover all of the generic and specific features of the invention herein described and all statements of the scope of the invention, which, as a matter of language, might be said to fall therebetween.
- 20 Having described my invention, what I claim as new and desire to secure by Letters Patent is:
1. In an apparatus of the character described, in combination, means for supplying and feeding a web, means for coating said web with an adhesive, and means for removing the surplus adhesive from said web comprising a scraper arranged in the path of the web, and means for adjusting 25 said scraper comprising a lever connected with said scraper, a spring engaging with one side of the lever, and a screw nut engaging with the opposite side of the lever.
  2. In an apparatus of the character described, in combination, means for supplying and feeding a web, means for coating said web with an adhesive and removing the surplus adhesive from said web comprising an adhesive supply pot and a delivery roller 30 adapted to turn with its lower part in the adhesive in the pot and deliver the same on its upper side to said web, a regulating roller around which said web passes, a rocking support for said latter roller, a spring 35 connected with said support and tending to move said regulating roller away from said pot and delivery roller, a catch engaging with said rocking support, and an adjusting mechanism connected with said catch.
  3. In an apparatus of the character described, in combination, a web supply, a plurality of tension rods with each of which the web contacts, web guides mounted on 40 said rods, means to adjust said guides toward and from each other, and glue supply means associated therewith.
  4. In an apparatus of the character described, in combination, a web supply, a supporting frame, tension rods projecting 45 therefrom each adapted to contact the web, web guides on said rods, means for adjusting said guides on said rods, and glue supply means associated therewith.
  5. In an apparatus of the character de-

scribed, in combination, a supporting frame, 65 spaced tension rods projecting therefrom, a guide on said rods, a second guide on said rods spaced from the first guide, means comprising a tension bar to adjust the second guide and glue-applying means associated 70 therewith.

6. In an apparatus of the character described, in combination, a supporting frame, a tension roller thereon, spaced tension rods carried thereby, a guide on the rods and 75 roller, a second guide on the rods and roller spaced from the first guide, means for adjusting the position of said guides and glue-applying means associated therewith.

7. In an apparatus of the character described, in combination, a glue pot, a roller therein adapted to supply glue to a web, an adjusting roller adapted to determine the contact between the web and supply roller, supporting arms for the adjusting roller 85 pivotally supported on the pot, a bracket supported on the pot, and tension rods supported by said bracket.

8. In an apparatus of the character described, in combination, a glue pot, arms 90 pivoted thereon, a roller carried by the arms, means tending to move the arms in one direction, and an adjustable catch device to limit the extent of such movement.

9. In an apparatus of the character described, in combination, a glue pot, arms 95 pivoted thereon, a roller carried by the arms, means tending to move the arms in one direction, an angle lever pivoted on the pot, a latch pivoted to the lever and engaging 100 the arms, and means to adjust the position of the angle lever.

10. In an apparatus of the character described, in combination, a glue pot, a scraper bar secured at one end to one side of the pot, 105 a pivotally mounted adjusting bar secured to the other side of the pot and to the other end of the scraper bar, and means to adjust the bar.

11. In an apparatus of the character described, in combination, a glue delivery 110 roller, means for feeding a web in contact with the roller, a scraper over which the web passes, an adjusting roller engaging the web, means to adjust the latter to vary the 115 extent of surface contact of the web and delivery roller, and means to align the scraper with the web.

12. In an apparatus of the character described, in combination, a glue delivery 120 roller, means to feed a web in contact therewith, movable means adapted to vary the extent of surface contact of the web and roller, and means adapted to set the latter means and permit movement of the varying 125 contact means without varying the setting means.

13. In an apparatus of the character de-

scribed, in combination, a glue delivery roller, means to feed a web in contact therewith, a movable adjusting roller, means to set the adjusting roller with respect to the 5 delivery roller, and means adapted to permit relative movement of the rollers without changing the adjustment of the setting means.

14. In an apparatus of the character described, in combination, a delivery roller, means to feed a web in contact therewith, pivotally supported arms, a web adjusting device carried by said arms, yielding means adapted to move the arms in one direction, 15 and setting mechanism adapted to limit the movement of said arms under the influence of the yielding means.

15. In an apparatus of the character described, in combination, a glue delivery roller, means to feed a web in contact therewith, pivotally supported arms, a web adjusting device carried by said arms, yielding means adapted to move the arms in one direction, and setting mechanism adapted 25 to limit the movement of said arms under the influence of the yielding means, comprising a movable engaging member.

16. In an apparatus of the character described, in combination, a glue delivery 30 roller, means to feed a web in contact therewith, pivotally supported arms, a web adjusting device carried by said arms, yielding means adapted to move the arms in one direction, and setting mechanism adapted to 35 limit the movement of said arms under the influence of the yielding means, comprising a pivotally mounted hook and means to adjustably position said hook.

17. In an apparatus of the character described, in combination, a glue pot, a glue 40 delivery roller mounted therein, means to feed a web in contact with said roller, arms pivotally mounted on said pot, an adjusting roller carried by said arms, and setting 45 mechanism for fixing the operative position of the adjusting roller.

18. In an apparatus of the character described, in combination, a glue pot, a glue 50 delivery roller mounted therein, means to feed a web in contact with said roller, arms pivotally mounted on said pot, an adjusting roller carried by said arms, and setting 55 mechanism for fixing the operative position of the adjusting roller, comprising an elbow lever, a hook pivotally mounted thereon and adapted to engage said arms, a rod pivotally attached to the lever, and means for adjusting said rod.

19. In an apparatus of the character described, in combination, a glue pot, a glue 60 delivery roller therein, guide rods pivotally connected thereto and adjustable toward and from each other, means to support the rods in predetermined position relative to

the pot and tension rods supported by said 65 guide rods.

20. In an apparatus of the character described, in combination, a glue pot, a glue delivery roller therein, guide rods pivotally supported thereby and adjustable toward 70 and from each other, tension rods supported by said guide rods, and braces between said pot and said tension rods.

21. In an apparatus of the character described, in combination, a glue pot, a glue 75 delivery roller therein, guide rods pivotally supported thereby and adjustable toward and from each other, tension rods supported by said guide rods, arms depending from said guide rods and adapted to rest against 80 the pot to form braces for said tension rods.

22. In an apparatus of the character described, in combination, a glue delivery roller, means for feeding a web in contact with the roller, a tension device adapted to 85 operate on the web in advance of the glue roller, an adjusting roller adapted to contact the web in rear of the glue roller, a scraper adapted to contact the web intermediate the adjusting roller and the glue 90 roller, and means adapted to adjust the adjusting roller and the scraper, whereby the extent of surface contact of the web with the glue roller and the angle of deflection between the web and the scraper may be va- 95 ried.

23. In an apparatus of the character described, in combination, a glue pot, a roller therein adapted to supply glue to a web, a web tensioning device carried by said pot 100 comprising a bracket, spaced tension rods laterally projecting therefrom, web guides threaded on said rods, and means to relatively adjust said guides.

24. In an apparatus of the character described, in combination, a glue pot, a roller 105 therein adapted to supply glue to a web, a web tensioning device carried by said pot comprising a bracket, spaced tension rods laterally projecting therefrom, adjustable 110 web guides threaded on said rods, and a tension rod joined to one of said guides and adjustable therewith.

25. In an apparatus of the character described, in combination, a glue pot, a roller 115 therein adapted to supply glue to a web, a web tensioning device carried by said pot comprising a bracket, tension rods carried thereby, a tension roller carried thereby, and relatively adjustable web guides 120 threaded on said rods and roller.

26. In an apparatus of the character described, in combination, a glue pot, a roller therein adapted to supply glue to a web, a web tensioning device carried by said pot 125 comprising a bracket, laterally adjustable parallel rods carried thereby, guide rods transversely supported on the tension rods,

and means for relatively adjusting the guide rods.

27. In an apparatus of the character described, in combination, a glue pot, a roller 5 therein adapted to supply glue to a web, a web tensioning device carried by said pot comprising a bracket, laterally adjustable parallel rods carried thereby, guide rods transversely supported on the tension rods, 10 a tension rod joined to one of said guide

rods, and adjustable securing means between the last-mentioned rod and the other guide rod.

In testimony whereof I affix my signature, in the presence of two witnesses.

CARLOS HOLLY.
